UNITED STATES PATENT OFFICE.

ADAM WOEGER, OF DENVER, COLORADO.

TIP FOR VEHICLE SHAFTS, POLES, AND THE LIKE.

1,061,436.

Specification of Letters Patent.

Patented May 13, 1913.

Application filed February 17, 1912. Serial No. 678,202.

To all whom it may concern:

Be it known that I, ADAM WOEGER, a citizen of the United States, residing at Denver, in the county of Denver and State of Colorado, have invented certain new and useful Improvements in Tips for Vehicle Shafts, Poles, and the Like; and I do declare the following to be a full, clear, and exact description of the invention, such as 10 will enable others skilled in the art to which it appertains to make and use the same.

This invention relates to improvements in tips for the shafts and poles of vehicles.

One object of the invention is to provide 15 a tip or ferrule for the ends of vehicle shafts, poles, neck yokes and the like having means whereby the tip may be adjusted to compensate for the shrinkage of the end of the shaft or other object to which it is 20 applied thereby keeping the tip tight and preventing noise which occurs from the rattling of the tip when loose.

Another object is to provide a tip of this character having means whereby the same 25 will engage and protect the outer end of the leather covering of the shaft or pole.

With these and other objects in view, the invention consists of certain novel features of construction, and the combination and 30 arrangement of parts as will be more fully described and claimed.

In the accompanying drawings; Figure 1 is a side view of the outer end of a vehicle shaft showing the invention applied there- 35 to; Fig. 2 is a central longitudinal section thereof; Fig. 3 is a cross section on the line 3—3 of Fig. 1; Fig. 4 is a detail perspective view of one of my improved tips.

Referring more particularly to the drawings, 1 denotes my improved tip or ferrule which may be formed of any suitable material and the outer surface of which may be of any desired shape or configuration. The tip or ferrule is here shown and is prefer- 45 ably of tapered or frusto-conical form and is closed at its outer end, and has on its inner end an annular enlargement 2 which may be of any desired length and which provides between its inner expanded wall 50 and the adjacent side of the shaft or pole an annular space 3 to receive the outer end of the leather covering 4 of the shaft or pole 5 whereby said end of the covering is effectually protected and prevented from be- 55 coming worn or torn and which will hold said end of the cover in tight engagement

with the shaft. The enlargement 2 has a shoulder 3' which is adapted to contact with the inner end of the covering 4, when the ferrule is adjusted its full length on the 60 shaft.

The tapered inside diameter of the tip or ferrule is slightly less than the diameter of the end of the shaft, pole or the like with which the tip is engaged, thus preventing 65 the tip from being pushed entirely onto the end of the shaft. In the outer end of the sleeve or ferrule is formed a screw hole 6 with which is engaged the head 7 of a tip adjusting screw 8. The screw hole 6 is pref- 70 erably reamed out and the head of the screw is preferably tapered to fit the reamed out hole 6 whereby the outer end of the head is flush with the adjacent surface of the ends of the tip. The screw 8 when thus 75 arranged is adapted to be screwed onto the end of the shaft or other object to which the tip is applied, thus forcing the tip back forcibly onto the end of the shaft so that, should the tip become loose from the shrink- 80 age of the parts engaged thereby, this loose- 85 ness may be quickly and easily taken up and the tip again tightened by means of the screw 8 as will be readily understood. It will be also understood that in order to 85 permit this adjustment of the tip, a sufficient space 9 will be left between the outer end of the shaft and the inner wall of the outer end of the tip and that the space between the end of the leather cover and the inner end of the 90 enlarged portion of the tip will also be suf- 95 ficient to permit the tip to be forced back onto the end of the shaft or pole.

From the foregoing description taken in connection with the accompanying draw- 95 ings, the construction and operation of the invention will be readily understood without requiring a more extended explanation.

Various changes in the form, proportion and the minor details of construction may 100 be resorted to without departing from the principle or sacrificing any of the advantages of the invention as claimed.

Having thus described my invention, what I claim is;

The combination with a shaft or the like of a vehicle having a leather covering se- 105 cured a suitable distance from the outer end of the shaft, of a ferrule mounted directly on the shaft and provided on its inner end with an enlargement which is of greater di- 110 ameter than that of the ferrule,—the outer

end of the ferrule being spaced from the outer end of the shaft and also spaced from the outer end of the covering so as to adjust the ferrule and its enlargement respectively on the shaft and on the covering, said enlargement having a shoulder at its intersection with the ferrule which is adapted to contact with the inner end of the covering when the ferrule is adjusted its full length on the end of the shaft, and means inserted through the end of the ferrule and

into the end of the shaft whereby to hold the ferrule and its enlargement in an adjusted position.

In testimony whereof I have hereunto set my hand in presence of two subscribing witnesses.

ADAM WOEBER.
